UPTURN-AND-PULLBACK BOLT-ACTION FIREARM

Arthur A. Rowley, Hamden, Conn., assignor to
Winchester Repeating Arms Company, New
Haven, Conn., a corporation of Maryland

Application March 21, 1934, Serial No. 716,588

3 Claims.

(Cl. 42—16)

This invention relates to an improvement in bolt-action firearms, and particularly to bolt-action firearms of the upturn-and-pullback type wherein the firing-plunger is projectable through 5 the rear end of the breech-bolt.

In the event of the rupture of primers of cartridges being fired in firearms of the type referred to, the resultant blast would drive the firing-pin or -plunger rearwardly with such violence as to, 10 in some instances, actually eject the same from the firearm and thus endanger the marksman and possibly others. The rupturing of cartridge-primers, while infrequent, is a potential source of danger, and may result from many different 15 causes, such, for instance, as a faulty primer, a burred firing-pin point, etc.

The main object of the present invention is to provide a firearm of the upturn-and-pullback bolt-action type having simple, reliable and effective means to guard against the possible tearing 20 loose of the firing-plunger or other firing member, in the event of a ruptured primer.

Other objects and advantages will appear to those skilled in the art from the following, considered in conjunction with the accompanying drawings and the appended claims.

In the accompanying drawings:

Fig. 1 is a broken view in side elevation of one form of upturn-and-pullback bolt-action firearm embodying the present invention;

Fig. 2 is a view mainly in vertical central section through the receiver, bolt and a portion of the barrel, and showing the firing-plunger in the position which it assumes at the instant of 35 the firing of a cartridge;

Fig. 3 is a similar view, but showing the firing-plunger forced rearwardly to a degree sufficient to tightly compress the firing-spring as the result of a "blow-back" incident to a ruptured cartridge-primer;

Fig. 4 is a transverse sectional view taken on the line 4—4 of Fig. 2;

Fig. 5 is a similar view taken on the line 5—5 of Fig. 2;

Fig. 6 is a broken perspective view of the firing-plunger, detached; and

Fig. 7 is a perspective view of the spring-abutment sleeve, detached.

The particular upturn-and-pullback bolt-action firearm herein chosen as illustrative of the present invention includes a skeletonized receiver 10 having a longitudinal passage 11 and a loading-and-ejection opening 12. Reciprocating in the longitudinal passage 11 of the receiver 10 is an oscillating-and-reciprocating bolt 13 having the

usual complementary pair of locking-lugs 14—14 at its forward end designed to have their respective rear faces respectively engaged with forward-facing locking-shoulders 15—15 formed at the junction of the longitudinal passage 11 before 5 referred to, and an enlarged bore 16 at the forward end of the said receiver.

Forwardly of the locking-shoulders 15—15, the said bore 16 in the receiver 10 is provided with internal threads 17 interengaging with similar 10 threads 18 formed upon the periphery of the shank 19 of the firearm-barrel 20. The rear end of the said barrel 20 is formed with the usual cartridge-chamber 21 for the reception of cartridges such as 22, having the usual primer (not shown) adapted to be struck by the firing-point 23 of a firing-plunger 24, which latter is mounted for reciprocation in a longitudinal passage 25 in the bolt 13 before referred to.

Adjacent its rear end the bolt 13 is provided 20 with a rigid offsetting bolt-handle 26 by means of which the said bolt may be oscillated and reciprocated in the usual manner of upturn-and-pullback bolt-action firearms. Immediately rearwardly of the bolt-handle 26 the bolt 13 is 25 provided with a detachable bolt-head 27 having a forwardly-extending externally-threaded sleeve-like extension 28 fitting within the internally-threaded rear end of the longitudinal passage 25 in the said bolt. The said bolt-head 27 under 30 ordinary conditions thus forms a part of the bolt 13 and for the purpose of description may be regarded as a unit therewith.

The firing-plunger 24 before referred to is 35 provided at its rear end with a head 29 and bears in the sleeve-like extension 28 of the bolt-head 27, so as to be guided thereby. Encircling the firing-plunger 24 is a helical firing-spring 30 bearing at its rear end against a spring-abutment 31 formed by the forward end of the sleeve-like extension 28 of the bolt-head 27, and bearing at its forward end against the rear end of a spring-abutment sleeve 32 fitted over the firing-plunger 24 and in turn bearing at its forward end against integral abutment-lugs 33—33 offsetting 45 at diametrically-opposite points from the said firing-plunger 24 adjacent the forward end thereof.

For the purpose of enabling the spring-abutment sleeve 32 to be maneuvered over the forward end of the firing-plunger 24 and properly seated against the forward faces of the lugs 33—33, the said sleeve is formed in its forward wall 34 with a polygonal passage 35 of such size and shape as to readily pass rearwardly over the 55

said lugs and into lateral registration with an annular groove 36 in the said firing-plunger. Upon being aligned with the said annular groove 36, the forward wall 34 of the sleeve 32 is given 5 one-quarter turn and upon again moving forwardly, the forward face of the said wall 34 will engage with the rear face of the abutment-lugs 33—33, and the polygonal passage 35 will be fitted over a squared portion 37 formed on the 10 firing-plunger and lying intermediate the abutment-lugs 33—33 and the annular groove 36, whereby the sleeve 32 will be held against both rotary and forward axial movement with respect to the firing-plunger 24.

15 The head 29, already referred to, of the firing-plunger 24 is formed on its underside with a forwardly-facing cocking-abutment 38 adapted to be engaged with the rear face of a sear-nose 39 upstanding from a pivotal sear 40, which requires no detailed description herein other than 20 to say that it is rocked for disengaging the said sear-nose 39 from the cocking-abutment 38 by means of a pivotal trigger 41.

Just forwardly of the head 29 of the firing-plunger 24, the periphery of the latter is formed with a relatively-long-and-shallow notch 42 having a forwardly-and-outwardly-sloping transversely-extending forward wall which constitutes a safety-abutment 43 engageable, under 30 certain conditions as will hereinafter appear, with a safety-abutment in the form of an abutment-pin 44. The said pin 44 is mounted tangentially in the bolt-head 27 so as to pass through the notch 42 for being engaged by the sloping 35 safety-abutment 43 just referred to. One end of the abutment-pin 44 is provided with an externally-threaded and kerfed head 45 fitting within an internally-threaded counterbore 46 forming the outer end of a tangential passage 40 47 into which the said pin 44 fits.

For the purpose of description, let it be presumed that the firing-plunger has just been released by the trigger 41 to the action of the firing-spring 30, which latter will thereupon drive 45 the firing-plunger forwardly to cause the firing-point 23 thereof to indent the primer (not shown) of a cartridge 22 in the cartridge-chamber 21 of the barrel 20, as indicated in Fig. 2 of the drawings. If, now, for any reason, the impingement 50 of the firing-point 23 upon the cartridge-primer should occasion the rupture of the latter, a blow-back of the powder-charge will occur and cause the firing-plunger 24 to be sharply driven rearwardly against the counterurge of the firing-spring 30, usually with sufficient force to tightly 55 compress the convolutions of the said firing-spring 30, as indicated in Fig. 3.

As thus positioned by the blow-back as just described, the now completely-compressed firing-spring 30 will form a solid abutment and throw 60 the full strain of checking the further rearward movement of the firing-plunger upon the portion of the front wall 34 of the spring-abutment sleeve 32 which is engaged with the abutment-lugs 65 33—33.

Under some conditions, the blow-back of burning gases as above described may be of sufficient force to occasion a breakage of the slender forward portion of the firing-plunger 24 or possibly 70 a shearing-away of the portions of the forward wall 34 of the spring-abutment sleeve 32 which are engaged with the abutment-lugs 33—33. In such event the firing-plunger, or at least the rear portion thereof, would be free for being forcibly 75 ejected from the rear end of the bolt 13, were

it not for the safety-abutment 43 and the abutment-pin 44, which are preferably so positioned with respect to each other as to interengage only after the firing-pin has been moved rearwardly sufficiently to completely compress the firing-spring 30, as indicated in Fig. 3.

If the breakage of the parts as above described should occur, the rearward travel of the firing-plunger will be definitely checked by the engagement of the safety-abutment 43 with the abutment-pin 44, and owing to the sloping character of the said safety-abutment 43, a jamming or wedging action will be exerted upon the abutment-pin 44 of such character as to effectively check the rearward motion of the firing-plunger.

From the foregoing it will be seen that the firing-spring 30 and the spring-abutments 31 and the rear end of the sleeve 32 constitute what may be appropriately termed a "primary stop" for checking the rearward travel of the firing-plunger. The features just referred to will ordinarily serve to completely check the rearward travel of the firing-plunger without any breakage of parts, so that the safety-abutment 43 and the abutment-pin 44 would not be interengaged 20 and consequently distorted under ordinary conditions.

In the event of an extremely severe rearward blow-back from a ruptured primer, or in the event of repeated blow-backs therefrom, the slender portions of the firing-plunger or the forward wall of the spring-abutment sleeve 32 may give way, in which case the safety-abutment 43 and the abutment-pin 44 will effectively prevent the ejection of the firing-plunger from 30 the arm and consequent injury to the marksman or others.

It may also here be noted that the firing-spring 30 does not become fully compressed so as to participate, with its associated parts, in acting 40 as a primary stop for the firing-plunger 24, until the latter has been moved rearwardly more than the distance required to interengage its cocking-abutment 38 with the rear face of the sear-nose 39.

By means of the embodiment of the present invention herein shown and described, the safety-abutments 43 and 44 are in effect "stand-bys" under ordinary conditions, and are not, therefore, subjected during the normal operation of 50 the firearm to such strains as might distort or weaken them and thus measurably reduce their capacity for effectively acting in an emergency, such, for instance, as when either an unusually-severe blow-back or oft-repeated blow-backs from ruptured cartridges take place.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended to be embraced therein.

I claim:

1. In an upturn-and-pullback bolt-action firearm, the combination with the bolt thereof; of a firing-plunger reciprocatable in said bolt and projectable from the rear end thereof; and two complementary interengaging safety-abutments, one of which is in the form of a transverse pin carried by and supported at each of its respective opposite ends in the said bolt and the other of which is of sloping form and carried by the

5 said firing-plunger and positioned so as to inter-
engage when and only when the said firing-
plunger is moved rearwardly beyond its cocked
position, to thereby guard against the rearward
ejection of the said firing-plunger from the said
5 bolt under the urge of a ruptured cartridge-
primer.

10 2. In a bolt-action firearm, the combination
with the reciprocatable bolt thereof, the said bolt
having a longitudinal firing-plunger-receiving
passage therein and also having a transverse
passage only partly intersecting the said firing-
plunger-receiving passage; a firing-plunger movable
15 in the firing-plunger-receiving passage of
the said bolt and projectable from the rear
end thereof, the said firing-plunger also having a
notch, the forward wall of which extends trans-
versely thereacross; and a transverse safety stop-
pin installed in the transverse passage of the
20 said bolt and laterally projecting partially into
the firing-plunger-receiving passage therein into
position to be engaged by the forward wall of
the notch in the said firing-plunger.

3. In a bolt-action firearm, the combination
with the reciprocatable bolt thereof, the said
bolt having a longitudinal firing-plunger-receiving
passage therein and also having a transverse
passage only partly intersecting the said firing-
plunger-receiving passage and extending into the
material of the said bolt on both sides of the said
firing-plunger-receiving passage; a firing-plunger
movable in the firing-plunger-receiving passage
of the said bolt and projectable from the rear
end thereof, the said firing-plunger also having a
notch, the forward wall of which extends trans-
versely thereacross; and a transverse safety stop-
pin installed in the transverse passage of the said
bolt and laterally projecting partially into the
firing-plunger-receiving passage therein into
position to be engaged, intermediate its respective
opposite ends, by the forward wall of the notch
in the said firing-plunger, the said safety stop-
pin being supported at each of its respective op-
posite ends in the said transverse passage in the
said bolt.

ARTHUR A. ROWLEY.
